UNITED STATES PATENT OFFICE

MARTIN J. STRAAYER, OF GRAND RAPIDS, MICHIGAN, ASSIGNOR TO GRAND RAPIDS SHOW CASE COMPANY, OF GRAND RAPIDS, MICHIGAN, A CORPORATION OF MICHIGAN

WALL-CASE CONSTRUCTION

Application filed October 4, 1926. Serial No. 139,319.

This invention relates to store furniture. It is concerned with an article of store furniture which may be utilized for supporting shelves on which goods may be placed for sale and display; or the same may be used to assemble, with the appearance and effect of a solid built structure, sectional units wherein goods may be placed for merchandizing or display.

10 It frequently happens that constructions of this character must be placed underneath balconies against the walls of a store, where in the vertical space is limited. It is one of the primary objects and purposes of the present invention to provide a construction which may be assembled underneath a balcony and make use of the entire vertical space available which heretofore has been practically impossible. Substantially all of the balconies

15 are provided with a socalled "overhang", that is, a moulding which extends downwardly at the under side and adjacent the front side of the balcony so that it is impossible to assemble the store furniture in front of the balcony and then bodily move the same to the rear, the overhanging moulding interfering with such procedure. With my invention it is possible to fully assemble the store furniture against the store wall and underneath the

20 balcony and at the same time make use of the entire space under the balcony, leaving no vacant space between the top of the store furniture construction and the under side of the balcony. This results not only in a saving of

25 space but presents a much better appearance and obviates the collection of dust and dirt at the upper side or top of the store furniture construction which must occur where space is left, usually of narrow width and hard

30 to reach for dusting or cleaning.

A still further object of the invention is to provide a construction of this kind which is relatively simple and economical to produce resulting in economies in manufacture. 45 Many other objects and purposes than those stated will appear as understanding of the invention is had from the following description taken in connection with the accompanying drawings, in which,

50 Fig. 1 is a vertical section through the store

furniture of my invention, the same being shown assembled underneath a balcony and against the side wall of a store, the balcony and wall appearing in dotted outline.

Fig. 2 is a similar view of the upper portion of said store furniture illustrating the manner in which the parts of the structure are assembled in the limited space available.

Fig. 3 is a fragmentary perspective view showing essential parts of the construction embodying my invention in disassembled relation.

Fig. 4 is a fragmentary enlarged vertical section at the upper front portion of the store furniture, the same being shown assembled.

Fig. 5 is a fragmentary plan view illustrating the method of connecting the horizontal units of the furniture at their junctions, and

Fig. 6 is a fragmentary plan and horizontal section through the furniture, the section being through a vertical frame located between the adjacent ends of horizontal units of the structure.

Like reference characters refer to like parts in the different figures of the drawings.

In the construction which embodies the invention, vertical frames are provided, each including a front post 1 and a rear post 2 connected at their upper and lower ends, respectively, by horizontal rails 3 and 4. The posts 1 and 2 have a plurality of spaced apart vertically aligned holes 5 therethrough with which adjustable shelf supporting bars 6 may be engaged, it being evident that the supports may be adjusted to different positions. The supports 6 and the method of adjustment are not new with this application and detailed description of the same need not be entered into.

The front post 1 at its front vertical edge is formed with a forwardly projecting tongue 7 of less thickness than the post. This tongue extends nearly the full length of the post 1 but at the upper and lower ends of the post recesses or notches are cut, as best shown in Fig. 3, the notch extending a short distance back of the rear portion of the tongue. Two plates 8 of metal of the form shown in Fig. 3 are attached by screws or equivalent fastenings, one at each side of and at the upper and lower

ends of the post 1 having lips which extend toward each other in front of the notched portion of the post, said lips, however, being separated by a vertical slot or groove 9.

The vertical frames thus described are adapted to be located in spaced apart relation substantially equal to the length of the shelves or units which are used in store furniture and are held in such relation at their front by an upper corner and a lower base rail, both being attached in substantially the same manner. The cornice includes a flat member 10 equipped at its front side and near its lower edge with a suitable ornamental moulding 11 if desired (though this moulding is not essential) and at its upper portion with a heavier moulding 12, the upper portion of which extends a short distance above the upper edge of the member 10. Also the ends of the mouldings 11 and 12 terminate a short distance from each end of the member 10, as shown in Fig. 3. At the rear side of each end of the member 10 a block 13 of wood is permanently secured, the upper end thereof lying flush with the upper edge of the member 10. This block extends a short distance beyond the adjacent end of the member 10 to which it is attached. In its rear vertical side a vertical groove 14 is cut leaving a tongue 15 between the groove and the adjacent vertical outer end of the block. When the cornice is applied to two of the spaced apart vertical frames described, the tongue 15 is received in the groove 9 while the projecting portion of the plate 8 enters the groove 14. With two of such cornices in alignment as shown in Fig. 5 the groove 9 is filled with the two tongues 15 on the abutting blocks 13. A horizontal opening is bored through each block 13 which, in the assembly of the structure, align with each other so that a bolt 19 threaded at both ends may be passed through the openings, receiving nuts which bind the blocks together. The cornice is completed at its underside by a rail 17 lying the full length of the member 10 underneath which is a horizontal finishing member 18, as shown in Fig. 4.

With the cornices applied in this manner a gap is left between the ends of the mouldings 11 and 12 and a narrower one between the adjacent ends of the members 10. Also the tongue 7 of the front post 1 is uncovered. A top 20 having a thickness equal to the distance that the moulding 12 projects above the upper edge of the member 10 is placed over the frames before the cornices are connected and shelves 21 may be located on the bars 6. The assembly is then completed by attaching a front finishing post 60 or pilaster 22 which is vertically grooved at its rear side making spaced apart flanges 23 between which the tongue 7 may be received. The upper ends of the flanges terminate substantially flush with the upper end of the tongue 7. The post is also equipped with two

oppositely extending lips 24 which overlap the front edges of the shelves 21 (see Fig. 6) covering said edges and completely disguising the joints so as to present a finished appearance and one which in effect makes the structure look as though solid built.

At the upper end of the post or pilaster 22 a vertical member 25 is secured, as shown in Fig. 3, at the upper end of which is connected a block 26. A vertical rib 27 is attached to the rear side of the member 25 and block 26, as best shown in Figs. 2 and 5. When the pilaster is applied with the flanges 23 passing one to each side of the tongue 7 the vertical rib 27 passes into the space between the adjacent ends of the two members 10 of the cornices in horizontal alignment and the block 26 fills the space between the adjacent ends of the mouldings 12 on said cornices, as shown in Fig. 5; while the lower end of the member 25 fills the space between adjacent ends of the mouldings 11 and is preferably finished so as to correspond with said mouldings.

The construction at the lower ends of the frames and the means for attaching the base board 29 between the lower ends of said frames is substantially identical with that described for use at the upper ends of the posts 1. That is, the base boards 29 are equipped with similar blocks 13, the post 1 recessed and equipped with the side plates 8. The binding together by means of the bolt 19 is used and in other respects the construction is a substantial duplicate.

In the assembly of store furniture of this construction underneath a balcony the vertical frames, consisting of the posts 1 and 2 and the rails 3 and 4 between them, are properly spaced apart and connected at their lower ends by the base boards or cornices 29. The lower shelf 21^a is applied as shown in Fig. 1 and the shelf supporting bars 6 added and shelves 21 placed thereon. The top 20 is then slid rearwardly into place underneath the balcony which is indicated at 30 in dotted lines in Figs. 1 and 2, Fig. 2 illustrating the said top in the process of being applied to the structure. The upper cornices are then added and secured together by means of the bolts 19 after which the front finishing posts or pilasters are added and secured in place by screws 28 which pass through either one or both of the flanges 23 into the tongues 7 and with the pilaster so applied and detachably held in place the members 25 at their upper ends overlap the cornice rails 10 and also retain the cornices in position.

A construction of this kind can be assembled against a wall indicated at 31 in dotted outlines, and underneath the balcony 30 irrespective of any downward projecting or overhanging moulding such as is indicated at 32 in Figs. 1 and 2. This is because the application of the parts is by a direct hori-

zontal rearward movement. There is no necessity to raise any part, such as the top 20 or the upper cornice or the finishing post or pilaster, above the position which it will occupy in the finished structure; and the entire vertical space between the under side of the balcony and the floor may be utilized as is evident from reference to Fig. 2. At the same time the construction is practical to 10 manufacture and assemble, economical in manufacturing cost and may be used either for the support of shelves or for the assembly of merchandise holding units such as indicated at 33, in Fig. 1. That is, should the 15 structure be used for units the shelves are merely replaced by the units either in the beginning or after the shelving structure has once been installed in a store. The units lie between the vertical spaced frames and the 20 front posts or pilasters 22 with the lateral lips 24 overlapping the adjacent ends of the units to completely cover and disguise the joints between the ends of the units and the posts, giving the appearance and effect of a 25 solid built structure.

The invention is defined in the appended claims and is to be considered comprehensive of all forms of structure coming within their scope.

30 I claim:

1. Store furniture comprising, a plurality of spaced apart vertical frames, upper cornices lying between and at the upper ends of adjacent frames, each of said frames being recessed at its upper front corner for said cornices whereby the cornices may be applied to the frame by direct horizontal movement of the same inward to said frames, means binding the abutting ends of adjacent cornices together and to said frames, and a pilaster detachably connected to and covering the vertical front edge of each of said frames and the abutting end portions of the cornices.

2. A construction of the class described 45 comprising, a plurality of spaced apart vertical frames, each comprising front and rear spaced apart posts connected at their upper ends by horizontal rails, each of said posts at its upper end having a portion removed to 50 provide a recess having vertical and horizontal sides located at a right angle to each other, and each of said front posts at its front edge being formed with a tongue extending substantially the full height of the post to said 55 recess, lower base boards connecting and spacing apart said front posts at their lower ends, cornices disposed in alignment between the upper ends of said frames having abutting end portions received in said recesses of the 60 front posts, means for binding the abutting ends of the cornices together, and pilasters, each formed at its rear face with a channel 65 groove into which said tongue of the front post of each frame may enter, one of said cornices being applied to each of the front posts

and detachably connected thereto, the upper end of each pilaster overlapping adjacent ends of the cornices attached to each frame.

3. Store furniture comprising, a plurality of spaced apart vertical frames, each including spaced apart front and rear posts connected at their upper and lower ends by horizontal cross rails, each of said front posts at its upper end having a right angle recess cut therefrom at its front, each being formed below said recess with a vertical tongue of reduced thickness, a plate secured to the upper end at each side of said front post, each of said plates extending beyond the rear side of the recess cut in the post thereby forming a 70 groove between the front edges of said plates, lower base boards disposed between and connecting the front posts adjacent their lower ends, upper cornices located one between each two adjacent spaced apart frames, each of 75 said cornices comprising a flat member, a block attached to the rear side and at each end of said flat member, said block having a vertical groove in its rear face and said block extending a short distance beyond the end of 80 the member to which it is attached whereby when the cornices are applied the blocks on the adjacent ends of two aligned cornices engage at their vertical ends against each other and the projecting ends of said plates are 85 received in the grooves of said blocks, means 90 passing through the adjacent blocks for detachably binding the same together, and a vertical pilaster having a channel groove cut vertically in its rear side detachably attached to each of the front posts of each of said frames, the tongue being received in the 95 groove of the pilaster and at its upper end having a part which overlaps the adjacent ends of said cornices.

4. A construction containing the elements in combination defined in claim 3, each of 100 said members of the pilasters being equipped at its front side with a horizontal moulding, the upper side of which extends a short distance above the upper edge of said member, and a top disposed horizontally between the upper ends of two adjacent frames back of 105 said moulding, its upper surface lying flush with the upper surface of the moulding.

5. Knockdown store furniture comprising, 110 a plurality of spaced apart vertical frames having a predetermined height, a lower base board lying between and connecting said frames at the front end at the lower portions thereof, cornices lying between and connecting said frames at the front and at the upper ends thereof, a top separate from the cornice lying over and between each of two adjacent frames, the upper surfaces of the cornices and of the tops lying in the same horizontal plane, whereby said top is retained by said cornices, means for receiving and fastening said cornices to said frames without raising them 115 above the plane they will occupy in assem- 120 125 130

bled position, and a front pilaster applied to the front vertical edge of each frame and detachably connected thereto.

6. A construction containing the elements in combination defined in claim 5, said pilaster at its front being provided with laterally extending lips adapted to overlap and cover the joint between the same, and merchandise holding elements carried by and between said frames.

10. 7. Store furniture comprising, a plurality of spaced apart vertical frames, upper cornices lying between and at the upper ends of adjacent frames, means for receiving said 15 cornices on said frames by direct horizontal movement, a pilaster at the vertical front edge of each of said frames, means for receiving said pilaster on said frame by direct horizontal movement and means for detachably 20 connecting the pilaster to the frame.

In testimony whereof I affix my signature.
MARTIN J. STRAAYER.
